2,094,409

APPLICATOR FOR ARTIFICIAL EYELASHES

Festus B. Phillips, Sr., Westwood, Calif.

Application May 21, 1935, Serial No. 22,502

14 Claims. (Cl. 132—1)

My invention relates to an applicator for use in holding artificial eyelashes during application thereof, as well as to an applicator and artificial eyelash former, and an object of my invention is 5 to provide a novel device of this character which will facilitate the application of artificial eyelashes to the human eyelid and greatly relieves the heretofore tedious fitting of artificial eyelashes.

10 An object is to provide a novel applicator of the above character which arranges and holds the artificial eyelash in the proper shape conforming to the eyelid and enables the attaching margin of the artificial eyelash to be applied 15 evenly and inconspicuously.

An object is to provide a novel device of this character which may be used with safety and which minimizes the danger of injuring the eyelid or eyeball or causing the artificial eyelash or 20 the adhesive used to secure it from coming in contact with the eyeball.

Another object is to provide a novel applicator for artificial eyelashes which serves also as a means for easily and quickly measuring the 25 length of the natural eyelash so that the artificial eyelash may be cut to the desired length before applying the same.

Another object is to provide a novel applicator which incorporates a novel forming device 30 for aiding in pressing or curling the artificial eyelash preparatory to applying it.

Another object is to provide a novel applicator of the above character which may be used to apply mascara or dye to the natural eyelash or to 35 serve as a guide for marking or lining the natural eyelid.

Heretofore in the art of make-up of actresses and individuals either in the moving picture studios, on the stage, or in ordinary life, it has 40 been found desirable to add artificial eyelashes and lining to the natural eyelid to accentuate the eyelash and eyelid and the addition of additional (or artificial) eyelashes to the natural eyelashes has encountered considerable difficulties in that 45 the artificial eyelash could not be properly held during application and had to be applied by forcing the base or selvedge edge of the artificial eyelash with an adhesive applied thereto against an eyelid with a stick and that resulted in considerable flinching of the eye and was a tedious 50 operation that consumed considerable time before being successfully completed; and an object of my invention is to overcome such difficulties and enable a person not necessarily skilled in the 55 application of artificial eyelashes to apply the

same in a simple, expeditious and effective manner, as well as to provide a novel device that may be used in lining the natural eyelid and providing means for forming or curling the hairs thereof as well as applying mascara to the natural 5 eyelashes, and artificial eyelashes either before or after association with the natural eyelashes.

Other objects, advantages and features of invention may appear from the accompanying drawing, the subjoined detail description and the 10 appended claims.

The accompanying drawing illustrates the invention in some of the forms I at present deem preferable.

Figure 1 is an enlarged plan view of my novel 15 eyelash applicator and former.

Fig. 2 is a longitudinal sectional view thereof taken through 2—2, Fig. 1, and showing the applicator in its normal or clamping position, but without having an artificial eyelash associated 20 therewith.

Fig. 3 is a side or edge elevational view thereof, and showing in dot and dash lines an open position thereof.

Fig. 4 is a front view thereof.

Fig. 5 is a further enlarged fragmentary sectional view analogous to Fig. 2, as taken on line 2—2, Fig. 1, but showing an artificial eyelash in position with a pressing or forming clip applied and associated therewith.

Fig. 6 is a perspective view of an artificial eyelash such as is applied to the human eyelid with my applicator.

Fig. 7 is a plan view of a modified form of my 35 artificial eyelash applicator.

Fig. 8 is a side or edge elevational view of the applicator shown in Fig. 7.

Fig. 9 is an enlarged fragmentary sectional view taken on line 9—9, Fig. 7, and showing by heavy dotted lines the transverse position assumed by an artificial eyelash clamped therein.

An artificial eyelash such as used with my applicator usually comprises a selvedge edge or thin band 1 to which are tied or otherwise secured a plurality of hairs 2 simulating the natural eyelash hairs. My applicator is in the form of a clamp which securely holds the artificial eyelash without distorting its shape for application to the eyelid and with the selvedge edge 1 exposed to receive an alcohol soluble adhesive, which is 45 preferably an adhesive that is not soluble in water.

In the structure shown in Figs. 1 through 5, a pair of coacting clamp members 3 and 4 are provided which are relatively flat and broad at one end. The clamp members are provided with 50

55

concave or arcuate eyelid conforming edges 5. At the other end of the clamp members 3, 4, handle portions 7, 8 are respectively formed or provided.

Between the handle portions 7 and 8 and the arcuate or concave edges or margins 5, 6 each clamp member is bent slightly outwardly from the other as indicated at 9. The clamp members are pivotally connected together in any suitable manner as by the coacting lug and pin means 10 that extend from opposite edges of the handle portions and such pivoted connections form a hinge for permitting clamping movement of the clamp members. Means in the form of a spring 11 which may be positioned between the extremities 15 of the handle portions are provided and such means urge the margins 5 into contact with each other.

The marginal portions 5 are reduced toward their edges to form a feather edge which may be 20 a relatively sharp but a non-cutting edge. The upper clamp member 3 is provided with a large arcuate slot 12 which conforms to the marginal portion 5 so that said marginal portion is in the form of a narrow strip. The lower clamp member 4 is provided with an arcuate rib or projection 13 which is adapted to extend upwardly through the slot 12 in conformity therewith; that is, its forward side 14 facing the margins 5 and 6 is concaved both horizontally as well as vertically 30 and approximates the desired form of the artificial eyelash. The distance from the crest of the rib 13 down its forward side and to the extremities of the marginal portions 5 are approximately or slightly greater than the length of the 35 hairs 2 of the artificial eyelash. The eyelash is adapted to be positioned between the marginal portions 5 of the members 3, 4, with its selvedge 1 protruding. The hairs 2 can then be properly arranged against the forward side 14 of the rib 13. 40 Sometimes the artificial eyelashes become out of curl or out of shape through handling or other instrumentalities, or when initially made up they are usually straight. If this be the case they can be made into or returned to their proper shape, 45 as the case may be, before being applied; this may be accomplished by securing the lashes between the clamp members, and after properly arranging the hairs in the proper spaced relation, a clip 15 is fitted over the margins 5 and against 50 the forward side of the rib 13. Said clip 15 is formed of spring material and is bent upon itself intermediate its ends as at 6' so as to fit around and over the margins 5 and form upper and lower 55 spring clamp elements 16 and 17 which hold the marginal portions 5 against each other as shown in Fig. 5. The upper spring clamp element 17 is provided with an upturned hair pressing portion 18 which conforms to the forward side 14 of the rib 13 to hold and press the strands of hair forming 60 the eyelash into place. While so held the hairs may be steamed or otherwise treated to cause them to retain their form.

In applying an artificial eyelash to the eyelid, the eyelash is placed between the clamp members 3 and 4 so that the selvedge thereof protrudes from the arcuate edges 5 and then the selvedge 1 is coated with a suitable non-water but alcohol soluble adhesive. The applicator and lash therein is then carefully placed immediately above the 70 natural eyelash and the selvedge 1 brought into contact along its entire length with the eyelid immediately above the roots of the natural eyelash and the adhesive brought into contact with the flesh. The excess or slack skin, if any, of the eye- 75 lid may be folded over the top of the selvedge

while the applicator and artificial eyelash are held in position. The artificial and natural eyelashes are then combed so that they intermingle.

In order to insure proper length and arrangement of the artificial eyelash, the extremities of the upper marginal portion 5 are provided with scale markings 19 as shown in Fig. 1. The scale markings 19 are first used to measure the length of the natural eyelash in order that the artificial one may be cut to the same length. These markings are next used to position the artificial eyelash properly in the applicator so that when the applicator with the eyelash therein is placed in position to attach the artificial eyelash to the eye the artificial eyelash will be properly positioned to 15 correspond to the natural eyelash.

In Figs. 7, 8, and 9 is illustrated a modified form of my artificial eyelash applicator, the structure there illustrated also comprises two clamp members, here designated 21 and 22, which are provided with complementary hinge elements 23 at their sides, connected by a hinge pin 24 around which is wrapped a spring 25. Said spring tends to hold the forward edges 26 and 27 of the clamp in contact with each other.

It will be understood that the type of spring 11 shown in Figs. 1, 2 and 3 may be used instead of the type of spring 25, or in Figs. 1, 2 and 3 I may use the type of spring 25 shown in Figs. 7-9. Said forward edges or margins are concave as at 30 5' in the same manner as in the first structure so that such concave edge will fit the curvature of the eyelid. However the upper or outer surface of the clamp member 21 is recessed as at 21' so that its forward surface is in the form of an arcuate downwardly and forwardly sloping lip or surface 21' as shown best in Fig. 9. The under or inner side 29 of this lip or margin conforms to the usual curve of the hair 2 as indicated by dotted lines a in Fig. 9.

At their ends opposite from the margins 26 and 27 the clamp members 21 and 22 are suitably shaped to form handle portions 30 and 31 which, when pressed together open the margins 26 and 27. As in the first described structure, the margins 26 and 27 may be provided with scale markings 19'.

Operation of the modified form of my applicator is essentially the same as the first structure, in that the selvedge 1 of the artificial eyelash is positioned so that it protrudes and may be coated with adhesive and applied.

Either construction of applicator may be used as a guide, when placed against the eyelid without the artificial eyelash therein, for the purpose of marking or lining the eyelid with an eye pencil or the like.

Also either of the applicators may be used in conjunction with the natural eyelash for the purpose of applying mascara. In such case the contacting parts of the margins 5 or 26 and 27 are preferably provided on at least one of such contacting surfaces with a narrow piece of felt or the like (not shown) and such felt or one or both of the marginal edges of the margins 5 or 26, 27 is coated with mascara and the natural eyelash is then extended between the clamp members. The applicator is then drawn away wiping the eyelash with mascara and at the same time removing any excess.

I claim:

1. In an artificial eyelash applicator; a pair of clamp elements having complementary artificial eyelid clamping portions provided with more or less feather edges and arranged to clamp

an artificial eyelash therebetween in position for application to an eyelid, the edges of said clamping portions substantially coinciding with each other.

- 5 2. In an artificial eyelash applicator; a pair of clamp elements having complementary artificial clamping eyelid portions provided with more or less feather edges and arranged to clamp an artificial eyelash therebetween in position for application to an eyelid; the edges of said clamping portions substantially coinciding with each other said portions having concave margins to substantially conform to the curvature of the natural eyelid.
- 10 3. In an artificial eyelash applicator; a pair of clamp elements having complementary eyelid clamping portions arranged to clamp an artificial eyelash therebetween in position for application to an eyelid; and an artificial eyelash hair retainer means associated with said eyelid conforming portions and adapted to receive the hairs of said artificial eyelash.

15 4. In an artificial eyelash applicator; a pair of clamp elements having complementary eyelid conforming portions arranged to clamp an artificial eyelash therebetween in position for application to an eyelid; the edges of said clamping portions substantially coinciding with each other and eyelash measuring means associated with

30 one of the eyelid conforming portions.

5 5. In an applicator for artificial eyelashes provided with a securing web or selvedge and eyelash representing hairs curving therefrom; a pair of coacting clamp elements, one of which is provided with a recess through which the hairs of the artificial eyelash may protrude without substantial distortion, whereby said clamp element may clamp said hairs adjacent said selvedge so that the selvedge may protrude from the 40 clamp elements for receiving adhesive and for application to the eyelid.

6 6. In an applicator for artificial eyelashes provided with a securing web or selvedge and eyelash representing hairs curving therefrom; a pair of coacting clamp elements, one of which is provided with a recess through which the hairs of the artificial eyelash may protrude without substantial distortion, whereby said clamp element may clamp said hairs adjacent said selvedge so that the selvedge may protrude from the clamp elements for receiving adhesive and for application to the eyelid; the extremities of said clamp elements conforming substantially to the curvature of the eyelid.

55 7. In an applicator for artificial eyelashes provided with a securing web or selvedge and eyelash representing hairs curving therefrom; a pair of coacting clamp elements, one of which is provided with a recess through which the hairs of the artificial eyelash may protrude without substantial distortion, whereby said clamp element may clamp said hairs adjacent said selvedge so that the selvedge may protrude from the clamp elements for receiving adhesive and for application to the eyelid; the extremities of said clamp elements conforming substantially to the curvature of the eyelid, whereby the selvedge of the artificial eyelash likewise conforms thereto; an eyelash measuring means incorporated along one 70 of said clamp elements.

8. In an artificial eyelash applicator; a pair of complementary clamp members hinged together intermediate their ends, handle means formed by one pair of said extended ends and 75 eyelash clamping elements formed at the other

pair of said extended ends, said clamping elements being beveled to a substantially feather edge and defining an eyelid conforming edge, and adapted to receive therebetween an artificial eyelash, the edges of said clamping portions substantially coinciding with each other.

5 9. In an artificial eyelash applicator; a pair of complementary clamp members hinged together at their intermediate portions, handle means formed by one pair of said extended ends 10 and eyelash clamping elements formed at the other pair of said extended ends, said clamping elements being beveled and defining an eyelid conforming edge, and adapted to receive therebetween an artificial eyelash; one of said clamp 15 members being slotted in conformity with its clamping element, and an eyelash forming rib extending upwardly through said slot from the other clamp member and having a forming surface confronting and continuing from said 20 clamping elements.

10. In an artificial eyelash applicator; a pair of complementary clamp members hinged together at their intermediate portions, handle means formed by one pair of said extended ends 25 and eyelash clamping elements formed at the other pair of said extended ends, said clamping elements being beveled and defining an eyelid conforming edge, and adapted to receive therebetween an artificial eyelash; one of said clamp 30 members being slotted in conformity with its clamping element, and an eyelash forming rib extending upwardly through said slot from the other clamp member and having a forming surface confronting and continuing from said clamp 35 elements; and a forming clip arranged to fit over said clamping elements and bear against the forming surface of said rib.

11. In an applicator for artificial eyelashes provided with securing webs or selvedges and eyelash representing hairs curving therefrom; clamp elements arranged to grip the eyelash hairs adjacent the selvedge; forming means for the extended portions of the hairs including a forming surface continuing from one of said clamp elements, and a device including a confronting portion arranged to press against said forming surface.

12. In an artificial eyelash applicator; a pair of clamping members; hinge means connecting the 50 clamping members, said clamping members having clamping portions terminating in eyelid conforming edges, one of said clamping members curving upwardly and away from its clamping member to permit an eyelash, while clamped to 55 occupy its normal shape.

13. In an artificial eyelash applicator; a pair of clamp elements having complementary artificial eyelid clamping portions beveled to a substantially feather edge and arranged to clamp 60 an artificial eyelash therebetween in position for application to an eyelid; one of said clamp elements being provided with a recess through which the hairs of the artificial eyelash may extend.

14. In an artificial eyelash applicator; a pair 65 of clamp elements having complementary artificial eyelid clamping portions beveled to a substantially feather edge and arranged to clamp an artificial eyelash therebetween in position for application to an eyelid; one of said clamp elements 70 being provided with a recess through which the hairs of the artificial eyelash may extend; and eyelash measuring means associated with one of said clamp elements adjacent said feather edge.
